(57) **CLAIM**

The ornamental design for a pair of shoes, as shown and described.

DESCRIPTION

FIG. 1 is a perspective view of the right-footed shoe of a pair of shoes showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the left-footed shoe of a pair of shoes showing my new design;

FIG. 9 is a front view thereof;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is a top view of a pair of shoes showing my new design; and,

FIG. 16 is a perspective view thereof.

The broken lines shown in the drawings depict portions of the pair of shoes that form no part of the claimed design.
